AIRSHIP GUARANTEE COMPANY, LIMITED, OF LONDON, ENGLAND, A BRITISH
COMPANY

RIGID AIRSHIP

Application filed August 19, 1927, Serial No. 214,036, and in Great Britain September 17, 1926.

This invention relates to rigid airships the object of the invention being to avoid torsion in the transverse frames and/or bending of the longitudinal girders.

5 As is well understood the longitudinal girders of a rigid airship extend from the bow to the stern of the ship and are intersected at intervals by the transverse frame members which latter are usually of the form of polygonal rings; a gas bag being located between each contiguous pair of transverse frames.

10 Each transverse frame is usually provided with a system of internal bracing wires (hereinafter termed the bulkhead wiring) which extend transversely across the frame and which interconnect the corners of the polygon. When a gas bag becomes deflated, the contiguous bag or bags tend to protrude laterally into the space formerly occupied by the deflated bag thus bringing considerable end pressure to bear on the bulkhead wiring and thereby setting up stresses which interfere with the stability of the transverse 15 frames, and/or which may also set up a bending moment in the longitudinal girders.

According to the present invention the parts of a rigid airship are so constructed or arranged that when in deflated gas bag 20 condition (due to one or more of the gas bags becoming deflated) the setting up of stresses, other than a direct compressional stress, in the transverse frames, due to the axial component of the end pressure on the bulkhead wiring, is avoided. To this end, and in cases where circumstances permit, such as is the case when the transverse frame is, for example, of rectangular, polygonal or like space frame cross section, or of triangular cross 25 section with the apex pointing outwards, the line of action of the bulkhead wiring can be arranged to pass through the neutral axis of the transverse frame members, by making the necessary connections to the neutral axes 30 of the said frame members, thus allowing the bulkhead wiring to move freely about the neutral axis of the transverse frame members. In such circumstances there will be no torsion in the transverse frame due to the end

pressure of the protruding gas bag on the bulkhead wiring.

Furthermore, and if the neutral axes of both the longitudinal girders and the transverse frame members are so arranged that they are coincident, i. e. by constructing the girders and the frame members in such a manner that their neutral axes coincide and by connecting the bulkhead wiring thereto at the points where the neutral axes of the transverse frame members and the longitudinal girders are coincident, the line of action 55 will also pass through the neutral axis of the longitudinal girder so that there will be no bending moment set up in the longitudinal girder.

It is not, however, always possible to establish the aforesaid conditions. For example, in cases where the transverse frame members are of triangular cross section with the apex pointing inwards. In such cases the ends of the bulkhead wires may be attached by means of catenaries or otherwise to some convenient point in the transverse frame members usually at the apex thereof, and consequently the line of action of the bulkhead wiring does not pass through the neutral axis of the transverse frame members when the bulkhead wires are deflected out of the plane of the transverse frame by pressure of the adjacent bags. Under these conditions and when in deflated bag condition the forces acting at each point of attachment of the bulkhead wiring to the transverse frame members can be resolved into two components, viz., a radial component acting in the plane of the transverse frame (i. e. transversely of the ship) and an axial component (i. e. acting axially of the ship). The axial component in the deflated bag condition sets up or tends 70 to set up torsion in the transverse frame members which torsion, in cases where the longitudinal girders and transverse frame members are rigidly interconnected, may in turn 75 set up a bending moment in the longitudinal girder.

To counteract this torsional component connections are made to the circumferential mesh wiring (which surrounds each gas bag) 80 from each point of attachment of the bulk- 85

head wiring to the transverse frame members, for example by means of strops. Consequently, and when a bag becomes deflated the force in the strop or other connection to the circumferential mesh wiring of the contiguous bag which remains inflated can be made equal and opposite to the axial component above referred to by suitably designing the circumferential mesh wiring of each gas bag, i. e. by varying the angle of the circumferential mesh wiring relatively to the axis of the ship, as described in our Patent No. 1,658,821. It will be understood that under these conditions the strop or other connection to the circumferential mesh wiring of the gas bag in the bag or section which contains the deflated bag will be slack. It will also be appreciated that when both the said contiguous gas bags are inflated the axis force in the connections between each pair of strops and the circumferential mesh wiring of the said contiguous bags will neutralize each other at each point of attachment to the transverse frame.

In order that the said invention may be clearly understood and readily carried into effect the same will now be described more fully with reference to the accompanying drawing, in which:—

Figure 1 shows diagrammatically the approximate position of the bulkhead wiring in deflated bag condition, as also that of the strops by means of which the bulkhead wiring is attached to the circumferential mesh wiring.

Figure 2 is a view illustrating the approximate position of the bulkhead wiring, and the strops under normal conditions when two contiguous gas bags are fully inflated.

Figure 3 is a partly diagrammatic perspective view showing in greater detail the position of the parts indicated diagrammatically at Figure 1.

A is one of the longitudinal girders (Figures 1 and 2). B, B are the transverse frame members. C is the bulkhead wiring which is located transversely of the airship between each contiguous pair of gas bags, and D, D¹ are the strops which connect the bulkhead wiring C to the circumferential mesh wiring E.

In the example illustrated the transverse frame members B are of triangular cross section, with the apex pointing inwards and the ends c, c, of the bulkhead wiring are attached by means of catenaries c², c³ to points equidistant apart around the transverse frame members, these points of attachment in the embodiment shown at Figure 3 being effected at the apex of the transverse frame members at the point where the transverse frame members are intersected by the longitudinal girders (not shown). Under these circumstances the line of action of the bulkhead wiring does not pass through the neutral

axis of the transverse frame members when the bulkhead wires C are deflected out of the plane of the transverse frame by pressure of the fully inflated gas bag in the bay or section next to that containing a deflated gas bag and to counteract the torsional component which is set up the strops D and D¹ are provided. In the example illustrated the circumferential mesh wiring is also provided with catenaries e the ends e¹, e² of which are attached to the strop D, the ends e³, e⁴ of the catenary e in a contiguous bay being attached to the same point c on the transverse frame by means of the strop D¹.

In the example shown the circumferential mesh wiring is of the type described in Patent No. 1,658,821, while the bulkhead wiring C is provided with a system of tight and slack radial wires as described in co-pending application Serial No. 214,328, filed August 30, 1927. c³, c⁴ are the slack radial wires of the bulkhead wiring and c¹, c² are the tight radial wires of the bulkhead wiring. D⁴, D⁴ are jack stays forming part of the circumferential mesh wiring E and which connect the ends of the strops D, D¹ to the corresponding strops on the next transverse frame members.

What we claim and desire to secure by Letters Patent of the United States is:—

1. A rigid airship comprising in combination longitudinal girders and transverse frame members, bulkhead wiring connected to the said members, circumferential mesh wiring and strops connecting said circumferential mesh wiring to said members at each point of attachment of said bulkhead wiring.

2. In a rigid airship, the combination of transverse frame members of triangular cross-section with their apices pointing inwardly and longitudinal girders so arranged relatively to said transverse members that their neutral axes intersect, bulkhead wiring connected to the internal periphery of each transverse member at points such that when the said wiring is lying within the plane of said transverse member the prolongation of the direction of each wire passes through one of the points of intersection of said axes; with circumferential mesh wiring connected to the transverse frame members at each point of their attachment to the bulkhead wiring.
